UNITED STATES PATENT OFFICE.

ALONZO E. RHOADES, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

WARPING-MACHINE.

1,254,936.

Specification of Letters Patent. Patented Jan. 29, 1918.

Application filed June 19, 1915. Serial No. 35,068.

To all whom it may concern:

Be it known that I, ALONZO E. RHOADES, a citizen of the United States, residing at Hopedale, county of Worcester, State of 5 Massachusetts, have invented an Improvement in Warping-Machines, of which the following description, in connection with the accompanying drawing, is a specification, like characters on the drawing representing 10 like parts.

This invention relates to warping machines and more particularly to warping machines of the type such as illustrated for example in the patent to Rhoades No. 624,541 15 granted May 9, 1899. Such machines are commonly provided with a stop motion mechanism which is actuated in either of two ways. First by the completion of the passage through the machine of a predetermined length of warp, and second by the 20 absence or failure of any warp end. When the stop motion mechanism has been actuated and the warping machine stopped it can usually be re-started by some simple 25 manual operation such as the depression of a foot lever. It frequently happens that the operative thus re-starts the machine and when the stopping of the machine has been occasioned by the completion of the measurement 30 of the predetermined length of warp such re-starting causes more warp than is desired to be wound off. The present invention is designed primarily to guard against this difficulty and the object of the 35 invention is to lock the warping machine in its inoperative position or to lock it against re-starting when it has been stopped by reason of the completion of the measurement of the predetermined length of warp rather 40 than by reason of the absence or failure of a warp end; or from another point of view the object is to provide a plurality of means requiring separate manual operation to enable starting of the warping machine after 45 the actuation of the stop motion mechanism due to completion of the measurement of the predetermined length of warp.

These and other objects of the invention will appear more fully from the accompanying description and drawings and will be particularly pointed out in the appended 50 claims.

In the drawings, Figure 1 is an end elevation of a warping machine of usual construction disclosing only so much of the mecha-

nism as is necessary to an understanding of the present invention;

Fig. 2 is a detail in front elevation of some of the parts directly concerned with a specific embodiment of this invention; 60

Fig. 3 is a perspective detail to illustrate the stop motion mechanism.

The construction of warping machine illustrated in the drawings for the purpose of disclosing a preferred form of the present 65 invention is substantially that of the warping machine illustrated in the beforementioned patent to Rhoades No. 624,541 and a reference to said patent will render unnecessary a detailed description here of the 70 machine.

The end frame 1 carries the continuously operated rock shaft 2 having the upwardly projecting rocker arm 3 which through the medium of the pawl 4 actuates the ratchet 5 which in turn through the medium of the worm 6, worm wheel 7, shaft 8, worm 9, and worm gear 10 drives the warp measuring mechanism, or as it is commonly known, the "warper clock". This mechanism in the 80 form illustrated includes a spirally grooved barrel 11 and a finger 12 mounted to slide on a rod 13. The finger 12 rides in the groove of the barrel 11 and when the predetermined length of warp has been measured 85 this finger rides out of the groove in the barrel and is rocked about the rod 13 by the weight 14 thus swinging the left hand end of the finger upwardly, and this movement is availed of to actuate the stop motion 90 mechanism.

The means employed for effecting the stopping of the warping machine are in the form illustrated substantially the same as disclosed in the aforesaid patent to Rhoades. 95 The starting and stopping shaft 15 carries a rocker arm 16 pivotally connected at its free end with the elbow lever 17 which in turn is loosely connected to the sliding rod 18, which rod at its outer end carries the 100 belt fork 19. According, therefore, to the direction in which the shaft 15 is rocked the belt is shifted from the fast pulley 20 to the loose pulley 21 and vice versa. A weight 22 connected to the shaft 15 is preferably employed to effect the stopping of the machine by shifting the belt onto the loose pulley and the machine is started by manually rocking the shaft 15 in the opposite direction. For the latter purpose a treadle 23 is 105 110

usually employed and rigidly connected with the shaft 15.

The starting and stopping shaft 15 has fast upon it outside the frame 1 the arm 24 to which is pivotally connected at 25 the shipper rod 26 extended through a suitable notched holding plate 27 on the frame, and this rod 26 is provided with a shoulder 28 to engage the underside of the plate and 10 maintain the stop motion mechanism inoperative when the machine is running.

A knock off lever 29 is pivoted on the frame in such a position that when its upper end is drawn rearwardly or to the right in 15 Fig. 1 the lower end engages the shipper rod releasing it from the notched plate and allowing the said rod to rise vertically through the plate and the machine to be stopped through the action of the weight 22.

20 The operation of the knock off lever and consequently of the stop motion mechanism is effected as has been stated either by the completion of the measurement of a predetermined length of warp or by the absence 25 or failure of a warp end. For this purpose the rocker arm 3 has pivotally mounted upon it at 30 the latch 31 shown as a bent lever, the right hand or upper end of which when in contact with the upwardly extending pro- 30 jection 32 from the rocker arm 3 holds the latch in such a position that as the rocker arm 3 swings backwardly and forwardly the forward or left hand end of the latch is above the knock off lever 29. If, however,

35 the latch is not held against the projection 32 it will at once drop in front of the knock off lever 29 and upon the return movement of the rocker arm will operate the knock off lever to effect the stopping of the machine.

40 The latch is normally held against the pro- jection 32 by the vibrating arm 33 ful- crumed at 34 and weighted at 35. This vi- brating arm is provided with bars 36 ex- tending in the usual way in the path of the 45 drop wires 37 so that if any drop wire falls the vibrating arm is caught and locked when its lower end has swung to the left. This vibrating arm is also provided with a pin 38 coöoperating with a notched arm 39 secured

50 to the finger 12 or to a rod 40 projecting therefrom. When the finger 12 rides out of the groove in the barrel 11 upon the completion of the measurement of the predetermined length of warp this arm 39 is rocked

55 to bring its notched end into the path of the pin 38 so that by this means also the vibrating arm 33 is caught and locked when its lower end has swung to the left. In both cases it will be seen that the latch 31 is released and swings on its pivot 30 to fall in front of and effect the operation of the knock off lever 29.

If, therefore, the stop motion has been actuated for either reason, that is, because 65 the predetermined length of warp has been

measured off or because some one or more of the filling ends have failed or become broken the machine is stopped. The operative places his foot on the treadle 23 and by depressing the treadle starts the machine. 70 When the warp end has been broken or fails this does no harm because the piecing of the warp is attended to by the operative and the measurement of the warp remains unchanged, but if the stoppage has been due to 75 the completion of the predetermined length of warp such a start of the machine causes further amount of warp to be wound off which is very undesirable. Nevertheless 80 the operatives are very likely thus to restart the machine. The present invention provides against such a re-starting of the machine and the preferred form of mechanism employed for that purpose is shown as a device for engaging the shipper rod 26 and 85 locking it in elevated position when it has been actuated as the result of the completion of the measurement of a predetermined length of warp, but this locking means is so arranged as not to be operated when the machine has stopped because of the absence or 90 failure of a warp end. It will thus be seen that in the former case a plurality of independent manual operations are necessary in order to permit the machine to be re-started 95 and this prevents the operative from unconsciously or carelessly re-starting the machine.

A bracket 41 is bolted to the side frame of the machine and on this bracket is fulcrumed at 42 a bell crank lever 43. An arm 44 is connected to the lower arm of the bell crank lever 43 and projects downwardly and is offset at 45 to rest against the side of the shipper rod 26. The shipper rod is provided at a suitable point with a notch 46 to co-operate with this offset end. A U-shaped lever is fulcrumed at 47 in the bracket 41 and has one arm 48 projecting out over the rod 40 of the finger 12 and its other arm 49 normally resting on the shoulder 50 of the upper arm of the bell crank lever 43, thus holding the offset 45 out of engagement with the notch 46. If now the predetermined length of warp is measured off and the finger 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

thus holds the shipper rod locked in elevated or inoperative position. If, however, the stopping of the machine is effected by the absence or failure of a warp end the rod 40 5 will not be raised, and consequently there will be no locking of the shipper rod when it rises into elevated or inoperative position.

In order, therefore, to restart the machine after the stop motion has been actuated due 10 to the completion of the measurement of the predetermined length of warp it is necessary first to remove the offset end 45 of the rod 44 from the notch in the shipper rod, and second, to depress the treadle 23. Thus 15 a plurality of, in this case two, independent or separate manual operations are required.

Having fully described my invention, what I claim as new and desire to secure by Letters Patent is:

20 1. In a warping machine comprising warp measuring mechanism, warp end absence or failure detecting mechanism, stop motion mechanism actuated both by said measuring mechanism upon the completion of a predetermined length of warp and by said detecting mechanism upon the absence or failure of a warp end, said stop motion mechanism comprising a longitudinally movable shipper rod provided with a shoulder, means engaging said shoulder to prevent actuating movement of said rod and thus maintain the stop motion mechanism inoperative, a knock-off lever for said rod, means to engage said rod in and maintain it in actuated position, and 25 30 35 means actuated by the measuring mechanism upon the completion of a predetermined

length of warp to actuate said knock-off lever and cause said engaging means to engage said rod.

2. In a warping machine comprising warp 40 measuring mechanism, warp end absence or failure detecting mechanism, stop motion mechanism actuated both by said measuring mechanism upon the completion of a predetermined length of warp and by said detecting mechanism upon the absence or failure of a warp end, said stop motion mechanism comprising a reciprocable starting and stopping member, locking means coöperating with said member, a pivotally mounted U-shaped lever one arm of which controls said locking means and the other arm of which is controlled by said measuring mechanism whereby the measuring mechanism upon its actuation of the stop motion mechanism 45 50 55 operates the U-shaped lever to lock the starting and stopping member in inoperative position.

3. A warping machine comprising warp measuring mechanism, stop motion mechanism 60 actuated both by the said measuring mechanism upon the completion of a predetermined length of warp and also by the absence or failure of a warp end, and means including a U-shaped pivoted lever to lock 65 the warping machine in inoperative position actuated by the measuring mechanism upon the completion of a predetermined length of warp.

In testimony whereof, I have signed my 70 name to this specification.

ALONZO E. RHOADES.
